AUTOMATIC TAIL WINDER FOR YARN
PACKAGESAlbert E. Winslow, Greenville, S. C., assignor to
J. P. Stevens & Co., Inc., a corporation of Delaware

Application June 28, 1948, Serial No. 35,576

11 Claims. (Cl. 242—18)

1

This invention relates to a winder, twister, or the like, and more particularly to a means for winding a tail on a package for transferring the yarn from one package to another in the winding of the yarn on a beam or the like.

In the provision of a tail on the end of a yarn package it has been quite usual for the operator to manually wind the tail on the outside of the package and then set the machine in operation for providing the main part of the package. This operation usually results in the provision of a tail longer than is necessary and the uneven lengths of tails in different packages due to the human element of varying the length of material desired. Further, the time of the operator is consumed in this operation, and frequently because of handling of the yarn along this tail portion the same becomes soiled. Further, the twist may vary to an undesirable degree where a twisted yarn is used.

One of the objects of this invention is to provide a device for winding the tail on the outer end of the head of a yarn package without the constant attendance of the operator, and to automatically transfer the yarn from the groove where the tail is provided to the main part of the package for continued winding.

Another object of the invention is to control the length of the yarn which is wound for the tail of the package.

Another object of the invention is to provide a tail which will be less soiled or dirty because of contact with the operator's hands.

Another object of the invention is to provide a yarn which will be less varied in twist than where wound manually.

Another object of the invention is to reduce the waste because of the exact length which is provided in the tail groove for tying and transferring in any of the following processes.

With these and other objects in view the invention consists of certain novel features of construction as will be more fully described and particularly pointed out in the appended claims.

In the accompanying drawings:

Figure 1 is a sectional view of a fragmental portion of a winding machine which is equipped with this invention;

Figure 2 is a front view of a portion of the winding machine;

Figure 3 is an elevation with a part of the casting removed of the operating mechanism which is the subject of this invention, with the guiding finger in raised position;

Figure 4 is a view similar to Figure 3 but show- 55 vided.

ing the guiding finger started on its downward movement;

Figure 5 is a sectional view on line 5—5 of Figure 3;

Figure 6 is a sectional view on line 6—6 of Figure 3;

Figure 7 is an elevation of the guiding finger alone; and

Figure 8 is an elevation of a modified form of package.

In proceeding with this invention I have provided a guiding finger for directing the yarn out of the path of travel which would normally occur in the winding of the yarn on the take-up package and then have provided for a movement of this guiding finger after a certain predetermined time so that the yarn will be released therefrom to resume its normal path of travel and then wind on the take-up package core to provide the package of the required size leaving the inner end available as a tail for joining to the outer end of another package for continuous winding of the material in some subsequent process to which the yarn is subjected.

With reference to the drawings, 10 and 11 designate parts of the framework of a twisting or winding machine which is of a length to mount a multiple of winding units, each of which receives power from a shaft extending the length of the machine which in turn is driven from a single source. Brackets 12 support a driving shaft 13 extending the length of the machine along which driving drums 14 are located for driving the take-up package designated generally

30 15 and which has its trunnions supported in grooved arms 17 to have the core 18 gravitate into surface engagement with the driving drum 14 for rotating the package. Each package spool is equipped with heads 19 and 20 and on the outer end of the head 20 there is a grooved flange

40 21 for winding the tail of the package. An end retaining pin 22 is provided on this flange for securing the end thereto. This grooved flange is notched as at 23 for the passage of yarn there-

45 24 through onto the core 18 for winding by being traversed on this core. A traverse comprising a porcelain guide 25 is notched as at 26 for the reception of the yarn therein, which guide

50 25 is reciprocated by a movement of the bar 27 on which it is mounted so as to direct the movement of the yarn from head to head of the package. A wire yarn guide 28 from one traverse guide 25 to the next traverse guide 25 is pro-

The device which is primarily the subject of this application is designated generally 30 (see Figures 3 to 5) and comprises a casing 31 which has two parts 32 and 33 which are brought together and secured to house the contents thereof. Secured to this casing there is also an arm 34 across which the yarn may be directed for engagement with the traverse 25.

A constantly rotating shaft 36 extends lengthwise of the machine parallel to the shaft 13 upon which the various driving drums are mounted. At a location opposite each of the grooved flanges 21, I provide a gear 37 (see Figures 3, 4, and 5) which is mounted upon the shaft 36 to continually rotate therewith. In this casing 31 which surrounds the gear 37, I mount upon a shaft 38 a mutilated gear 39 having several teeth thereof missing, so that when the mutilated portion is adjacent the gear 37, there will be no driving movement imparted to the mutilated gear 39. A pin 40 is provided on this gear 39 and a finger 41 slidably mounted in the casing 30 which when in up position as shown in Figure 3 will project a substantial distance above the casing 30. This finger is enlarged at its lower end as at 42 and provided with a slot 43 of a shape best shown in Figure 7 into which the pin 40 on the gear 39 extends. The lower wall of the slot 43 is provided with an arcuate depression 47, and the opposite wall portion of the slot 43 opposite to said depression 47 extends on an upwardly directed curvature providing a cam surface 48. In the normal position of the finger 41, the pin 40 engages in the said depression 47 which is at a position to be vertically in line with the center of rotation of the said gear 39, the said pin being positioned opposite to the mutilated portion of the gear 39 (see Fig. 3). A spring 44 pulls this finger upwardly and as the finger is moved downwardly, this spring is placed under tension tending to move the finger again upwardly. Upon the applying of a manual downwardly force on the finger 41, the cam surface 48 thereon will move into engagement with the pin 40 on the left thereof as viewed in Fig. 3 to turn the gear 39 in a clockwise direction to place its tooth 45 in position to be engaged by the gear 37 which will now rotate gear 39 and through pin 40 engaging the lower wall of the slot 43 continue the downward movement of the finger 41. After the pin 40 has been carried past lower center of the gear 39, the finger 41 will be free to be moved upwardly under the urge of spring 44 but held back by the pin 40. Upon said gear 39 being moved out of engagement with the gear 37, the finger 41 under tension of spring 44 will continue to be moved upwardly and moving therewith the pin 40 to continue the turning of the gear 39 until the force of the spring 44 on the pin 40 is directly vertical of the center of rotation of gear 39 and said pin is again in engagement with the said depression 47 as shown in Fig. 3. When the finger is in its lowermost position, its top end 51 will be substantially flush with the raised portion 49 of the casing and by reason of the curved surface would permit the yarn 52 to slide over this portion and over the top end 51 of the finger 41.

In use, yarn 52 will be drawn from a spindle (which is not shown) upwardly through the pig-tail guide 53 which is located in a plane at right angles to the axis and substantially centrally of the take-up package 15. The operator will then lead the yarn over the guide 34 as shown at the left in Figure 2 and wrap the same about the

pin 22, then start the package in operation and give a slight pressure on the guide finger 41. The unit may from this point on go unattended and the operator may go to attend to replenishing another package. After starting, the yarn will be drawn through the notch 23 in the grooved flange and wound into the groove 21 just so long as the yarn is engaged and deflected by the finger 41, as shown at the left in Figure 2, where the yarn now designated 51' being shown at an angle from the guide 53 to the guide 41. This guide 41 is being drawn downwardly as the operation proceeds and when the guide 41 gets to a level which is below an imaginary line from the arm 34 to a tangent to the top of the grooved flange 21 it will slide over the top 51 of the guide finger and then by reason of its angular relation to the guide 53 will be drawn through the notch 24 in the head of the package and then will rest upon the core of the package 18 and will also slide over the end of the arm 34 and be received in the traverse guide 25 so that as the yarn 52" as shown at the right in Figure 2, thereafter will continue on its usual course reciprocating the yarn back and forth between the heads 19 and 20 until the package is of the desired diameter, when a new one will be replenished and the cycle of operations will be continued.

In some cases it is unnecessary to have a spool with heads for the yarn package, and in Figure 8 I have illustrated a cylindrical core 60 having trunnions 61 at either end and with a groove 62 adjacent one end into which the tail portion of the package may be wound by being directed onto the package by the finger 41, after which the yarn will engage the traverse as heretofore mentioned to build up the package 63 into the desired size.

I claim:

1. In a winder, twister, or the like having a plurality of take-up packages, means for rotating said take-up packages, a reciprocally movable traverse for traversing the yarn lengthwise of the package to wind the yarn thereon, a stationary support adjacent each said packages, a tail winding guide slidably mounted on each of said supports for holding the yarn out of engagement with said traverse and for directing the yarn to be wound at one end of said packages for forming a tail thereon, a common drive means extending through said supports, and driven means within each of said supports operatively connected to said guides and movable independent of each other for slidably moving the guide associated therewith to release the yarn held thereby from engagement therewith a predetermined time after started in operation to permit said yarn to be engaged by said traverse.

2. In a winder, twister, or the like as in claim 1 wherein said tail winding guide comprises a finger slidably mounted for movement in a generally vertical direction.

3. In a winder, twister, or the like as in claim 1 wherein said tail winding guide comprises a finger slidably mounted for movement in a generally vertical direction and said driven means for moving said finger comprises a mutilated gear to engage said common drive means for drawing said finger downwardly.

4. In a winder, twister, or the like as in claim 1 wherein said tail winding guide comprises a finger slidably mounted for movement in a generally vertical direction and resilient means for automatically returning said finger to the upper position thereof after drawn downwardly sufficiently to release said yarn.

5. In a winder, twister or the like, means for rotating a take-up package, a reciprocally movable traverse for traversing the yarn lengthwise of a package to wind the yarn thereon, a stationary housing, a guide movably mounted on said housing and normally at a position for holding the yarn out of engagement with said traverse and for directing the yarn to be wound at one end of said package for forming a tail thereon, a normally continuously rotating gear in said housing, a mutilated gear in said housing rotatable by said rotating gear and normally out of engagement therewith, means carried by said mutilated gear and connected to said guide for moving the same to release the yarn from engagement therewith upon rotation of said mutilated gear, and means carried by said guide and movable therewith for engaging said first means for moving said mutilated gear into engagement with said rotating gear.

6. In a winder, twister, or the like, means for rotating a take-up package, a reciprocally movable traverse for traversing the yarn lengthwise of the package to wind the yarn thereon, a movable guide normally at a position for holding the yarn out of engagement with said traverse and for directing the yarn to be wound at one end of said package for forming a tail thereon, said guide having a slot therein, a gear having a pin eccentrically mounted thereon and extending into said slot for engagement therewith for moving said guide to a position to release the yarn engaged therewith upon rotation of said gear to permit said yarn to move to a position to be engaged by said traverse, and means for rotating said gear.

7. In a winder or the like, means for rotating a take-up package, a reciprocally movable traverse for traversing the yarn lengthwise of the package to wind the yarn thereon, a guide slidably mounted and normally held at a position for holding the yarn out of engagement with said traverse and for directing the yarn to be wound at one end of said package for forming a tail thereon, said guide having a slot therein, a mutilated gear having a pin eccentrically mounted thereon and extending into said slot for engagement therewith for moving said guide to a position to release the yarn engaged therewith upon rotation of said gear to permit said yarn to move to a position to be engaged by said traverse, and a normally continuously rotating gear engageable by said mutilated gear for rotation therewith, and means including said pin and guide for moving said gears into engagement.

8. In a device for winding yarn upon a rotatable take-up package comprising a slidably mounted guide finger normally held at a position for holding the yarn out of its normal path of travel as being wound on said package and for directing the yarn to be wound at one end of said package for forming a tail thereon, mechanically operable means manually initiated for moving said guide finger from said normal position to a location to permit the yarn engaged therewith to escape therefrom to move into its normal path of travel, and resilient means for automatically re-

turning said guide finger to said normal position after the release of said yarn therefrom.

9. In a device for winding yarn upon a rotatable take-up package comprising a slidably mounted guide finger normally held at a position for holding the yarn out of its normal path of travel when being wound on said package and for directing the yarn to be wound at one end of said package for forming a tail thereon, a mutilated gear operable upon the rotation thereof for moving said guide finger from said normal position to a location to permit the yarn engaged therewith to escape therefrom to move into its said normal path of travel and resilient means for automatically returning said guide finger to said normal position after the release of said yarn therefrom.

10. In a device for winding yarn upon a rotatable take-up package comprising a slidably mounted guide finger having a slot therein and normally held at a position for holding the yarn out of its normal path of travel when being wound on said package and for directing the yarn to be wound at one end of said package for forming a tail thereon, a mutilated gear having a pin eccentrically mounted therein and extending into said slot and operable upon the rotation thereof for moving said guide finger from said normal position to a location to permit the yarn engaged therewith to escape therefrom to move into its said normal path of travel and resilient means for automatically returning said guide finger to said normal position after the release of said yarn therefrom.

11. In a device for winding yarn upon a rotatable take-up package comprising a slidably mounted guide finger having a slot therein and normally held at a position for holding the yarn out of its normal path of travel when being wound on said package and for directing the yarn to be wound at one end of said package for forming a tail thereon, a mutilated gear having a pin eccentrically mounted thereon and extending into said slot and operable upon the rotation thereof for moving said guide finger from said normal position to a location to permit the yarn engaged therewith to escape therefrom to move into its said normal path of travel and resilient means for automatically returning said guide finger to said normal position after the release of said yarn therefrom, a continuously rotating gear, and cam means on said finger engageable with said pin for moving said mutilated gear into engagement with said rotating gear to be rotated thereby.
